ELECTRICALLY-HEATED DEVICE.

1,105,962.

Specification of Letters Patent.

Patented Aug. 4, 1914.

Application filed December 4, 1913. Serial No. 804,639.

To all whom it may concern:

Be it known that I, FREDERICK E. CARLSON, a citizen of the United States, and a resident of New Britain, in the county of Hartford, State of Connecticut, have invented certain new and useful Improvements in Electrically-Heated Devices, of which the following is a specification.

This invention relates particularly to an electrically heated device of cylindrical shape, such for example as can be conveniently used as a curling iron, which embodiment of the invention has been selected for illustration and description. It is also adapted for other uses, such as the heating of water, by placing it in the container which holds the water.

In the drawings—Figure 1 is a side view of a combined curling iron and comb made in accordance with my invention. Fig. 2 is a sectional view on the line 2—2 of Fig. 1, looking in the direction of the arrow. Fig. 3 is a longitudinal sectional view of the device with the comb and clip removed. Fig. 4 is an elevation view of the heating element with parts broken away to show construction. Fig. 5 is a transverse sectional view thereof on the line 5—5 of Fig. 4. Fig. 6 is a side view of the comb attachment. Fig. 7 is an end view thereof.

Describing the embodiment of the invention selected for illustration, *a* denotes the handle having a longitudinal bore within which is secured a sleeve *b* preferably of polygonal shape, which projects from the front of the handle for a short distance as indicated at *c*, and stops short of the rear end of the handle.

d is the curler which is a hollow cylindrical body which may be slightly tapering as shown in the drawings and is of a size to fit closely within the sleeve but having a small area of contact therewith owing to the polygonal shape of the sleeve which may conveniently be hexagonal as shown. What may be termed the shank of the curler is of reduced diameter between the ends of the sleeve as indicated at *e* in Fig. 2, the shank thus having a bearing in the sleeve for a short distance at each end and being out of contact therewith throughout the greater part of its length, thus preventing direct conduction of heat from the shank to the sleeve and so to the handle. At the end of the shank there is secured a bushing *f* to

which an insulating sleeve *g* is secured, which covers up the circuit connections with the heating element.

At diametrically opposite points in the projecting end *c* of the sleeve *b* key slots *h* are formed. The clip *i* customarily used with the curler has oppositely projecting pins *j* which can be slid into the key slots and held in position in the slight enlargement at the ends thereof by the spring *k* located underneath the thumb piece *l*, the spring also normally holding the clip down onto the body of the curler as clearly seen in Fig. 1. This provides a convenient and simple method of detachably assembling the clip with the curler.

The comb *n* has a cylindrical back *o* the diameter of which is slightly smaller than the diameter of the curler, and is longitudinally slotted throughout its length as at *p* in order that it may hug the body of the curler very closely and more readily take the heat. At the end of the comb there is provided a polygonal socket *s* of a shape corresponding to the shape of the sleeve *b* and which is adapted to fit onto the projecting end *c* of the sleeve to hold the comb against turning movement.

The heating element comprises a thin flat core *2* of insulating material, such as mica, about which is wound the resistance material which may conveniently be a coil of wire as indicated at *3*, against which other strips of mica *4* are laid to separate the wire coil from the strips of conducting material *6*, *6*, from the edge or edges of which spring the curved yielding flanges *7*, which are so shaped as to give the heater a cylindrical form slightly larger than the interior of the body of the curler, with the result that these spring flanges being under slight compression when they are assembled with in the curler are pressed into intimate contact with the curler and provide an effective heat conducting path from the heater to the curler. As shown, these strips *6* have oppositely curved flanges from each edge, but it is of course immaterial how these flanges are formed so long as they are arranged to give a large area of contact with the inner wall of the body and provide an effective heat conducting path. The resistance wire is coiled only about that part of the heater which is located within the main body part of the curler, and the terminals *110*

of the coil are carried to the end of the heater where it projects from the rear of the handle, where they are connected with the circuit wires 10, 11, and covered by the insulating sleeve *g*.

In its broader aspect this invention provides an extremely effective and efficient heater in a small compass and one which is adapted for a variety of uses.

10 A particular utility of the invention is to be found in its use as a curling iron, heated comb, etc., and I do not wish it to be understood that the broader claims on the electrical heater are limited to its use in or as a 15 curling iron.

I claim as my invention:—

1. In a device of the character described, a handle, a sleeve of polygonal cross section mounted therein, a curler supported in the 20 ends of said sleeve and out of contact with the intermediate portions thereof, and a heating element located within said curler in heat conducting relation with the exposed part thereof.

25 2. In a device of the character described, a hollow cylindrical curler and an electrical heating element mounted therein, said element comprising a resistance material, heat conducting members located at the opposite sides thereof and in heating relation therewith, and curved resilient flanges springing from an edge of said members and conforming in shape and size to the interior of said curler.

35 3. In a device of the character described, a handle, a sleeve of polygonal cross section mounted in said handle and projecting from the front end thereof, a curler supported by said sleeve, key slots formed in the forward 40 end of said sleeve at diametrically opposite points, a clip coöperating with said curler and provided with pivot pins adapted to fit within said key slots, a spring adapted to hold said pivot pins in engagement with 45 said sleeve, a comb provided with an expandable tubular back adapted to fit upon said curler, a member of polygonal shape secured to the end of said comb and adapted in size and shape to fit the end of said sleeve 50 and hold the parts against relative turning motion, and an electrical heater located within said curler and in heating relation therewith.

4. In a device of the character described, 55 the combination with a handle and a hollow cylindrical curler supported thereby, and a heating element located within said curler and in heating relation therewith, of dia-

metrically opposite key slots at the forward end of the handle, and a clip provided with 60 pivot pins adapted to enter and interlock with said key slots, and a spring to hold said pins in engagement with said key slots and the clip in operative relation with the curler.

5. In a device of the character described, 65 the combination with the hollow cylindrical body, of an electrical heating element located therewithin, said heating element comprising a thin flat core of mica, a resistance wire coiled about said core, insulating material 70 laid against the sides of said coil, and strips of conducting material laid against the said insulating strips, and curved resilient flanges formed at the edges of said strips of conducting material, conforming in shape 75 and size to the interior of said body.

6. An electrical heater of the character described, comprising a cylindrical shell and a heating element located therein, said element comprising a resistance, a heat conducting member arranged in heating relation with the resistance, and a resilient flange at an edge of said member and shaped to conform to and be fitted against the wall 80 of the cylindrical shell.

7. In an electrical heater, a cylindrical shell and a heating element located therein, said element comprising a thin flat resistance member, heat conducting members arranged against the side of said element, and oppositely curving resilient flanges springing 90 from the edges of said conducting members, conforming in shape to the shape of said shell, said flanges being held under compression within said shell.

8. An electrical heater comprising a tapering cylindrical shell closed at one end, and a heating element removably located within said shell, said element comprising a resistance and a heat conducting member secured 100 in heating relation with said resistance and provided with a resilient edge flange shaped to fit within and against the wall of said shell.

9. An electrical heater comprising a cylindrical shell, a resilient member of heat conducting material whose cross section corresponds approximately to the shape of the inner wall of the shell and adapted to fit within said shell under slight compression, 110 and an electrical resistance in heating relation with said member.

FREDERICK E. CARLSON.
